WILMER H. WILLIS, OF LOS ANGELES, CALIFORNIA.

WALL TIE AND BOND.

Application filed February 9, 1926. Serial No. 86,983.

This invention has to do generally with wall structures and is more particularly concerned with wall structures which include a supporting frame covered with a facing which is either wholly or in part made up of cementitious material such as 5 stucco, concrete or mortar. For instance, the facing may be a solid mass of stucco or concrete, or it may be of mortar bonded brick. The invention lies in the provision 10 of a supporting structure and facing therefor, tied together in a particular manner, as well as in the tie member, per se.

Since the invention may be applied with 15 particular advantage to brick veneer walls, I have illustrated and will describe it as so applied, but this is not to be construed as limiting the invention, considered in its broader aspects, to this specific application.

Heretofore, the tie between the supporting 20 or lining structure and the facing of brick veneer walls has been accomplished through the use of angle clips, the vertical arms of the clips being nailed to the wooden supporting frame or sheathing, and the horizontal, corrugated arms of the clips being embedded in the mortar between vertically adjacent bricks. This method of tying the facing to the sheathing has the inherent 25 disadvantage that only the bricks immediately adjacent the clips are directly tied to the sheathing, and since obviously it is impracticable to apply the clips between other than a limited number of bricks, bricks intermediate the clips often become horizontally 30 displaced or shift away from the sheathing when the wall is jarred or vibrated. Those bricks farthest from the clips naturally shift the most, with the result that the facing bows outwardly between clips, and it then takes but a comparatively slight jar to strip 35 the facing from the sheathing. Such conditions arise with particular frequency in localities subject to earthquake shocks, 40 though even the jar of heavy traffic or the weaving of the wall frame during high winds also tend thus to separate the facing from the sheathing. Therefore, it is among the objects of the invention to provide a 45 form of tie wherein the bricks between anchor clips are tied to the clips and hence indirectly to the sheathing. This is accomplished generally by the provision of wires or rods extending from clip to clip, means 50 being provided to secure the clips and

rods from relative displacement. These rods being embedded in the mortar between bricks, serve not only to tie and bond adjacent bricks to one another and through 60 the clips to the sheathing, but also serve as general reinforcing members for the facing.

The particular nature of my improved tie and the method of applying it to a faced wall may be discussed to better advantage 65 in the following detailed description, reference being made to the accompanying drawings, in which:

Fig. 1 is a perspective view of a tie embodying my invention;

Fig. 2 is a plan view of one of the tie 70 clips with the connecting or reinforcing rods attached thereto;

Fig. 3 is a section on line 3—3 of Fig. 2;

Fig. 4 is a plan section taken through a building structure made in accordance with 75 my invention; and

Fig. 5 is a section on line 5—5 of Fig. 4.

First referring to Figs. 1, 2 and 3, I have shown my tie as including angle clips 10, preferably of thin sheet metal punch pressed 80 to form, which clips are held in spaced relation by reinforcing or tie rods 11, there preferably, though not necessarily, being more than one such rod.

Arms 12 and 13 of each clip preferably 85 extend at right angles with respect to one another, vertical arms 12 preferably being punched at 14 to take nails whereby the clip is adapted to be anchored to a supporting structure. However, it will be evident that 90 it is not necessary to the invention that these holes 14 be preformed in the clip since the metal may be of such gauge that it may be pierced by the nails when the clip is applied to a given wall.

While any suitable method of attaching rods 11 to horizontal clip arms 13 may be employed, I have shown a preferred method of attachment which has certain features of advantage over other types of connections 100 such as "spot welds". Tabs or tongues 15 are punched and pressed outwardly from arms 13 and then turned back over rods 11, as clearly shown in Fig. 3, to clamp the rods to the face of the arms. It will be noted 105 that the free ends 16 of clamping tongues 15 point toward vertical arm 12, or in other words, toward the wall to which the clips are to be applied. By reason of this arrangement, it is assured that displacement 110

of the rods outwardly from arms 12 or the structure to which said arms may be secured, is prevented.

The terminals 16 may be turned upwardly somewhat as shown in Fig. 3, though this is in no way essential to the invention, thereby providing an angular lip for each tongue which will have a superior hold in the mortar. By reason of the curvature of the tongues, it is also evident that there will be left openings 17 through arm 13 between the terminals 16 and the ends of the holes formed by punching out the tongues. These spaces 17 are adapted to receive mortar from above and beneath, and therefore, make provision for a superior mortar hold.

As stated at the outset, the invention may be applied to any structure made up of a supporting member or lining wall to which a cementitious facing is applied, clips 10 being nailed to the supporting member, and arms 13 projecting horizontally from said member. By then applying the facing to the wall, it will be seen that clips 10 and rods 11 form a general reinforcement for the facing and tie said facing to the supporting or lining wall, the clips and rods both, of course, being entirely embedded in the cementitious facing.

However, since the device may be applied with particular advantage to a brick veneer structure, I have illustrated it as so applied. Where a wall is veneered with brick, there are certain conditions which do not exist in a solid facing wall, and which are particularly well cared for by the application of my invention. For instance, since the brick veneer is made up of a plurality of separately applied units (bricks) there is much more likelihood of the facing parting from the sheathing, for there is always a tendency for the bricks to shift relatively when the wall is exposed to severe shocks or vibrations.

In Fig. 4 I have illustrated a typical wall structure made up of sheathing S applied to vertical studs T, these studs being horizontally spaced in the usual manner. The studs and facing may be considered, as a whole, as a supporting structure, while the sheathing, alone, may be considered as a lining wall. The structure shown in Fig. 4 is made up of walls A, B, C, D which are joined to form a building construction of closed outline, as viewed in plan.

Clips 12 are preferably so horizontally spaced that when the tie member is applied to the sheathing there may be a clip opposite each stud T and preferably one or more clips intermediate each stud. As the facing F is built up by applying one brick course 20 upon another, the bricks, of course, being laid with their inner faces against sheathing S and being bonded together with mortar M in the usual manner, tie member P, which

may be considered as made up of two or more clips 10 connected by one or more wires 11, are nailed at 21 to sheathing S, and, where they lie opposite the studs, through the sheathing to said studs. Thus, after a given brick course 20^a has been laid, tie P will be nailed to the sheathing just above this course, and then the next course 20^b laid in mortar on top course 20^a. The clips and rods are thus embedded in the mortar between courses 20^a and 20^b, and serve not only to tie vertically and horizontally adjacent bricks together and to the sheathing, but also serve as a general reinforcement for the veneer facing. Since the rods are surrounded on all sides by the mortar and are securely held to the clips, and the clips in turn securely nailed to the sheathing, it will be seen that the individual bricks as well as the adjacent courses, considered as a whole, are held against lateral displacement and their tendency to bow outwardly between clips is counteracted. Ties P may be vertically spaced any desired number of courses, depending upon the conditions of a given situation, but I find that ordinarily a tie member every fifth course suffices.

Where the ends of two walls meet, the terminals of the reinforcing rods 11 of the two walls are preferably connected together, as by twists 22 or in any other suitable manner, the facings on the two walls thus being tied not only to each other, but also to the two walls. Thus there may be a net work of reinforcing rods extending completely about a structure of closed outline, the net work being, in effect, continuous about the structure and thereby most effectually resisting all forces tending to displace any facing with respect to its particular supporting wall.

It will be understood the drawings and description are to be considered merely as illustrative of and not restrictive on the broader claims appended hereto, for various changes in design, structure and arrangement may be made without departing from the spirit and scope of said claims.

I claim:

1. In a tie for holding a facing having cementitious portions to an upright supporting structure, horizontally spaced clips adapted to be secured to said supporting structure and to extend horizontally from the outer face of said structure, and a tie rod connecting said clips, said clips and rod being adapted to be embedded in said cementitious portions.

2. In a tie for holding a facing having cementitious portions to an upright supporting structure, a plurality of horizontally spaced clips each of which includes arms bent substantially at right angles to one another, one arm of each clip being adapted to be secured to the supporting structure,

and a tie rod connecting the other arms of the clips.

3. In a tie of the character described, a plurality of spaced, sheet metal clips, and a rod connecting said clips, the connections between said rod and clips embodying tongues punched outwardly from the clip and bent over the rod to hold said rod to the clip.

10 4. In a tie of the character described, a plurality of spaced, sheet metal clips each of which includes a pair of arms disposed sub-

stantially at right angles with one another, a tie rod connecting similarly disposed arms of adjacent clips, the connections between said rod and arms embodying tongues punched outwardly from the arms and clamped over said rod, the free terminals of the tongues pointing towards the other arms of the clips.

In witness that I claim the foregoing I have hereunto subscribed my name this 8th day of January 1926.

WILMER H. WILLIS.
